UNITED STATES PATENT OFFICE.

CLYDE W. NAILOR AND GEORGE J. SOUTH, OF SCHENECTADY, NEW YORK.

VICE.

1,059,749.

Specification of Letters Patent.

Patented Apr. 22, 1913.

Application filed April 11, 1912. Serial No. 689,849.

To all whom it may concern:

Be it known that we, CLYDE W. NAILOR and GEORGE J. SOUTH, citizens of the United States, residing at Schenectady, in the 5 county of Schenectady and State of New York, have invented certain new and useful Improvements in Vises, of which the following is a specification.

Our invention relates to certain new and 10 useful improvements in vises, the primary object of the invention being to provide a construction of vise wherein the movable jaw is adjustable to practically instantaneously clamp or release the work.

15 A further object of the invention is to provide a simple, reliable and efficient construction and arrangement of adjusting, locking and releasing means whereby the movable jaw may be adjusted to firmly 20 clamp the work, locked in adjusted position and release for retraction, and automatically retracted upon being released.

A still further object of the invention is to provide means for limiting the opening 25 movement of the movable jaw and means for supporting the vise at a desired angle to the bench or support to which it is attached, as well as to construct a vise which affords a wide range of conveniences and 30 general efficiency.

The invention consists of the features of construction, combination and arrangement of parts, hereinafter fully described and claimed, reference being had to the accompanying drawings, in which—

Figure 1 is a side elevation, partially in section, of a vise embodying our invention, showing the movable jaw partially adjusted from its limit of outward movement toward 40 the fixed jaw. Fig. 2 is a vertical transverse section on a line through the vise body. Fig. 3 is a top plan view of the bed plate. Fig. 4 is a view showing the adjusting sleeve in cross section and the threaded plate in end elevation. Fig. 5 is an end elevation of the parts shown in Fig. 4. Fig. 45 6 is a fragmentary perspective view of the adjusting rod or shaft. Fig. 7 is a view of the retaining plate. Fig. 8 is a detail view 50 in side elevation showing a modification in the means for attaching the vise to a work-bench or table. Fig. 9 is a front elevation of the same.

Referring to the drawings, 1 designates 55 the upright body portion of the vise, which is provided at its lower end with a base

plate 2 and at its upper end with an anvil horn 3 and a fixed or stationary clamping jaw 4. The body portion is further provided with a pair of superposed guide openings 5 and an intervening passage 6, said guide openings and passages extending between its front and rear edges.

Arranged in advance of the body portion 1 is a head 7 provided with a bearing opening 8 in line with the passage 6, and also provided at its upper end with a movable jaw 9 for coöperation with said fixed or stationary jaw and at its lower end with a depending portion 10. Projecting from said head are superposed guide bars or shanks 11 which extend through and are slidably mounted in the guide openings 5 and carry at their rear ends a stop plate 12 adapted to abut against the body portion to limit the maximum range of outward movement of the jaw 9 with relation to the jaw 4.

Formed in the body portion and base plate is a socket 13 which receives the inner or rear end of a coiled spring 14, the outer or forward end of which bears against the part 10. This spring is adapted to be compressed by and on the inward movement of the movable jaw toward the stationary jaw and to exert its expansive energy to retract the head and open the movable jaw. The extent of retraction of the head and opening movement of said movable jaw may be varied and controlled by means of a stop pin 15, adapted to abut against the body portion 1 and to be passed through any one of a longitudinal series of transverse openings 16 in one of the guide bars or shanks 11. A chain or like flexible connection 17 connects the stop pin with the base plate, whereby its possible loss or displacement is prevented.

Suitably secured within the passage 6 is an internally threaded bushing 18 in which works an externally threaded adjusting and locking sleeve 19, which normally projects forward beyond the sleeve, as shown in Fig. 1. Journaled in the opening 8 and extending longitudinally through the sleeve and bushings is an adjusting and locking rod or shaft 20 terminating at its forward end in an apertured enlargement 21 in which is slidably fitted a headed handle bar 22 of ordinary type. Said rod or shaft is provided with a collar 23 which abuts against the head 7 to hold the same from inward sliding endwise movement and

which is spaced from the enlargement 21 to form an annular groove receiving a recessed retaining plate 24 secured to the head, whereby the rod or shaft is held from outward sliding movement.

5 The sleeve 19 is provided with diametrically opposed longitudinal clutch ribs 25 formed with cam faces 26 and square abutting surfaces 27, the latter having spaced recesses 28, while the rod or shaft 20 is provided with similar clutch ribs 29 having cam faces 30 and square abutting surfaces 31 formed with recesses 32, the square abutting faces of the ribs of the sleeve and rod 10 forming series of spaced interlocking lugs arranged opposite each other. By this construction a clutch connection between the sleeve and rod is provided whereby when the ribs 29 are spaced from and arranged 15 out of contact with the ribs 25 the rod may slide freely in either direction, for the quick adjustment of the movable jaw by hand manipulation to approximately clamping position and the retraction of the jaw by 20 the spring 14. After the movable jaw has been adjusted to approximately clamping 25 position by turning the rod or shaft 20 to the right the lugs 27 and 31 will be brought into interlocking engagement and couple 30 the sleeve to the rod, allowing the rod to be turned up on the threads of the bushing and the movable jaw to be adjusted to firmly 35 clamp the work, in which position said jaw will be locked. It will thus be understood 40 that a partial rotation of the rod to the left, to return it to normal position, will free the rod and unlock the movable jaw, thereby 45 releasing the work, and then by turning the rod farther to the left the cam surfaces 50 of the ribs will be brought into engagement, whereupon the sleeve may be turned back to normal position, in which operation the sleeve while rotating slides back on the rod in an obvious manner. By disposing the 55 pin 15 in one or the other of the openings 16 the range of opening movement of the jaw 9 may be varied according to the size of the work being operated upon.

In order to adapt the vise to be arranged 50 at any desired angle upon the work-bench or table 33, the base 2 is provided with a journal 34 arranged to turn in a bearing opening 25 in a bed-plate 36, which is formed with apertured lugs 37 for the passage 55 of fastenings to secure it to the bench or table. Depending from the journal is a bolt 38 which passes downwardly through an opening in the bench or table, said bolt being equipped at its lower end with a retaining nut 39 and washer 40, which nut 60 may be adjusted by a hand lever 41. The base plate may be drawn down tight against the bed-plate or the pivotal connection left sufficiently loose to permit the vise to be 65 turned to any desired position for conven-

ience in use. Pivoted to the base-plate is a gravity dog 42 adapted to be tilted outward to retracted position by a finger piece 43 and to ride upon the periphery of the bed-plate and drop into any one of an annular series of seat-recesses or slots 44 therein to hold the vise against rotary movement in the desired position of adjustment. This construction adapts the vise to be easily and quickly turned to extend at any angle as 70 may be found most desirable in operating upon the work.

If desired, the fastening parts above described may be dispensed with and the base-plate provided with a depending bracket 80 arm 45, as shown in Figs. 8 and 9. This bracket arm is formed with an inturned lower end 46 projecting under the top of the work-bench or table, said end 46 being formed with a guide opening 47. A stem 48 is slidably fitted at its lower end in said opening 47 and is provided with a clamping head 48' and an enlargement 49 formed with rack-teeth 50. Meshing with these teeth is a toothed segment 51 mounted on a pivot 90 pin 52 in a slot 53 in the arm and having an operating handle 54. By adjusting this handle downward or upward the head may be moved into and out of clamping position, this construction permitting the vise to be 95 readily attached to and detached from any ordinary type of bench or table.

Our improved vise is especially adapted for automobile repair work, but will be found generally useful for all kinds of work 100 and of great convenience and advantage for rapid work and in operating upon large or small objects where quickness and efficiency of action are desirable qualities.

Other advantages of the invention will be 105 manifest to those employing tools of this character.

Having thus described the invention, what we claim as new is:—

1. A vise including a body having a fixed 110 jaw and a threaded passage, a movable jaw slidably connected with the body, a threaded sleeve working in said threaded passage, means for variably limiting the opening movement of the movable jaw, and a rod 115 journaled on the movable jaw and extending through said sleeve, said rod and sleeve being provided with coupling elements normally free from engagement in one position, and engageable by reverse rotary movements 120 of the rod to respectively couple the two for reverse motions, in one of which the rod is locked from endwise movement and in the other of which the sleeve slides on while turning with the rod.

2. A vise embodying a body having a movable jaw and a threaded passage, a sleeve working in said threaded passage, and provided with diametrically opposed longitudinal clutch ribs having cam-shaped outer 125

surfaces and recessed abutting surfaces, a movable jaw, and a rod journaled on the movable jaw and extending through the sleeve and provided with similar clutch ribs 5 for coöperation with the ribs of the sleeve.

3. A vise embodying a body having a movable jaw and a threaded passage, a sleeve working in said threaded passage, and provided with diametrically opposed longitudinal clutch ribs having cam-shaped outer 10 surfaces and recessed abutting surfaces, a movable jaw, means for variably regulating the degree of opening movement thereof, and a rod provided on the movable jaw and 15 extending through the sleeve and provided with similar clutch ribs for coöperation with the ribs of the sleeve.
4. A vise including a base, an upright ris-

ing therefrom, a fixed jaw carried by said upright, a movable jaw having a shank 20 slideable through the upright, said shank being provided in rear of the upright with a longitudinal series of openings, a spring for retracting the movable jaw, and a pin adapted to be inserted through any one of said 25 openings for engagement with the upright to variably limit the opening movement of the movable jaw.

In testimony whereof we affix our signatures in presence of two witnesses.
